UNITED STATES PATENT OFFICE.

RUDOLPH KNOOPP, OF CEDAR GROVE, NEW JERSEY, ASSIGNOR TO FRANK J. QUIGAN,
INC., OF BROOKLYN, NEW YORK. A FIRM OF NEW YORK.

ELECTRIC CONDENSER.

Application filed June 19, 1922. Serial No. 569,364.

To all whom it may concern:

Be it known that I, RUDOLPH KNOOPP, a citizen of Czechoslovakia, and a resident of Cedar Grove, county of Essex, and State of New Jersey, have invented certain new and useful Improvements in Electric Condensers, of which the following is a specification.

This invention relates to an electric condenser and more particularly, to a variable capacity condenser for use in connection with radio telegraphic and telephonic apparatus.

It is the primary object and purpose of
18 my present improvement to provide an elec-
tric condenser of simple and compact con-
struction but of relatively great capacity and
which is capable of a very fine adjustment,
thus affording greater selectivity in tuning
20 between the receiving and sending station.

In one embodiment of my present invention, I provide opposed condenser plates between which a suitable dielectric is interposed and cam means for moving one of said plates relative to the other whereby a general adjustment of the capacity may be obtained. In conjunction with said condenser plates, I provide a second independently adjustable plate which may be positioned with relation to a fixed plate in electrical connection with the fixed condenser plate whereby a further and finer adjustment of the capacity may be obtained.

It is also a further general object of the invention to provide an electric condenser of small size for use in connection with portable wireless apparatus and in which the several parts are so constructed and arranged that they may be easily and quickly disassembled for the purpose of adjustment and repair without requiring the services of a skilled electrician.

With the above and other objects in view, the invention consists in the improved electric condenser and in the form, construction and relative arrangement of its several parts as will be hereinafter more fully described, illustrated in the accompanying drawings and subsequently incorporated in the subjoined claims.

In the drawings wherein I have shown one practical and satisfactory embodiment of the invention and in which similar reference characters designate corresponding parts throughout the several views.

Figure 1 is a front elevation of the condenser as embodied in a practical form for use in radio apparatus;

Figure 2 is an enlarged sectional view taken on the line 2-2 of Figure 3; 60

Figure 3 is a section taken on the line 3—3 of Figure 2;

Figure 4 is a detail section taken on the line 4-4 of Figure 3; and

Figures 5 and 6 are detail perspective views of the complementary cam parts for shifting the movable condenser plate. 65

In the development of radio apparatus and in particular, apparatus employed in wireless telephonic communication, it has been found that with the several types of condensers at present in use, it is frequently not possible to obtain the necessary fineness in adjustment or variation of the micra farad capacity in order to secure accurate tuning between the sending and receiving stations, I aim to overcome this difficulty by combining in a single instrument, primary and secondary independently adjustable condensing means whereby it is possible to secure a very minute variation in the capacity between the maximum and minimum, say from .001 micra farad to almost zero.

As herein shown, in a preferred embodiment of the invention I provide a body 85 plate 5 of hard rubber or other suitable insulating material which is fixed at one of its ends to a base 6. Upon one side of the plate 5 one end wall 7 of a housing or casing for the movable parts of the condenser is arranged, said wall having an offset annular marginal flange 8 which is suitably secured to the insulation plate 5. The body 9 of the housing or casing, which is preferably of cylindrical form, has its annular wall seated against the end wall 7 and is rigidly secured in fixed relation to said end wall by a series of tie-bolts 10. The end wall of the body 9 has a portion thereof pressed inwardly as indicated at 11, said 90 inwardly pressed wall portion extending through substantially 180°. 95 100

In a bearing 12 of insulating material centrally fixed in the end wall of the casing body 9, one end of a shaft 13 is rotatably supported. This shaft extends through a sleeve 14 which is loosely mounted in the insulation plate 5, one end of said sleeve being supported in a bearing collar 15 of insulating material which is fixed in an out- 110

wardly projected central portion 16 of the end wall 7. This sleeve terminates in an annular flange 17 engaged with the inner side of the collar 15 and is formed with a cam surface 18.

The movable condenser plate 19 is axially shiftable upon the shaft 13 and is provided with a complementary cam face 20 with which the cam face 18 on the end of the sleeve 14 coacts. Between this movable plate 19 and the end wall 7 which constitutes the fixed condenser plate, a sheet of mica or other suitable dielectric 21 is interposed. The dielectric may either be secured to the face of the wall 7 or it may be fixed upon the opposed face of the movable condenser plate 19. A coil spring 22 yieldingly urges the movable plate 19 towards the fixed condenser plate 7 and maintains the cam surfaces 20 and 18 in contacting relation. At diametrically opposite points the edge of the movable condenser plate 19 is notched as at 23 to receive the tie-bolts 10 and at one of these notches a mica strip 24 is fixed to said plate and is also provided with a notch 25 to closely receive one of the tie-bolts 10. The axially shiftable condenser plate is thus held against a rotative movement and also insulated from electrical connection to the fixed plate 7.

A suitable knob 26 is fixed upon the outer end of the sleeve 14 and carries an index finger or pointer 27 for movement over a suitable scale 28 which may be calibrated in units of capacity or may be simply marked off in arbitrary divisions, as shown in Figure 1 of the drawings.

Upon the shaft 13 within the housing or casing a collar 29 is fixed by means of the set-screw 20 and to one end of said collar a plate 31 is fixed, said plate being disposed closely adjacent to the inwardly projected section 11 of the end wall of the housing and having planetary movement in a parallel plane. An arm 32 of insulating material is arranged between the collar 29 and one end of the spring 22 and at its outer end is notched as at 33 to receive one of the tie-bolts 10. Upon the other end of the shaft 13 a suitable operating knob 34 is fixed whereby a rotary movement may be imparted to the condenser plate 31 independently of the shifting movement of the condenser plate 19 and said plate 31 thereby positioned with respect to the inwardly projected section 11 of the end wall of the housing. It will be understood that the plate 31 also has a circumferential extent of 180° and by adjusting said plate, a greater or less extent thereof may be positioned in opposed relation to the wall section 11.

Suitable terminals are provided for the circuit wires, said terminals being herein illustrated by the binding posts 35 and 36. The binding post 35 is insulated from the

metal wall of the housing or casing by the insulating block 37 and is connected by the copper conducting strip 38 with the movable condenser plates 19 and 31 through the shaft 13. The other binding post 36 is in direct electrical connection with the metal body wall of the housing and through said wall with the fixed condenser plate 7.

From the foregoing description considered in connection with the accompanying drawings, the operation of the condenser will be readily understood by those skilled in the art. A general adjustment of the capacity may be easily and quickly secured by rotating the sleeve 14 through the medium of the knob 26, the position of the pointer or index member 27 as it moves over the scale 28 being noted. In the rotation of this sleeve, the cam 18 on the inner end thereof coacting with the cam 20 of the movable condenser plate 19, shifts the latter plate axially along the shaft 13 and away from the fixed condenser plate, thereby spacing the face of one of the condenser plates from the dielectric 21. The capacity of course, will continue to decrease as the condenser plate 19 is moved away from the fixed condenser plate 7. In order to obtain a further and finer adjustment of the capacity to secure more accurate and sensitive tuning, the operator now turns the knob 34 to thereby move the secondary condenser plate 31 in a rotary path and change its position relative to the inwardly struck section 11 of the housing wall. In this adjustment, it is understood that the primary condenser plate 19 is maintained in the position to which it has been moved with respect to the fixed plate 7. Thus it will be readily seen that it is possible to secure a very fine variation in the capacity of the condenser. The co-acting cam elements 18 and 20 are so formed that in the rotation of the sleeve 14 through 180°, the shiftable condenser plate will be moved so as to change the capacity from .001 110 micra farad to approximately zero. Between these extremes various capacities may be secured by the proper positioning of the index or pointer 27 on the scale 28, and a further and finer adjustment can be obtained by the planetary movement of the secondary condenser plate 31.

The improved electric condenser as above described, comprises relatively few simply constructed parts which are very compact in arrangement so that the size of the device in its entirety is such as to render it particularly useful in connection with small portable radio receiving sets. Nevertheless it is apparent that the foregoing reference to a specific construction is merely suggestive and that the instrument might be constructed in various other sizes and the form and arrangement of the several elements modified in certain respects, without depart- 130

ing from the principle involved. It is accordingly to be understood that while I have herein disclosed a satisfactory and practical embodiment of the device, it may be constructed in various alternative forms without departing from the spirit and scope of the invention as defined in the appended claims.

I claim:

10 1. In an electric condenser, a metal casing having an inwardly struck wall section constituting a fixed condenser member, a second metal condenser member rotatably supported within said casing, and means for 15 adjustably positioning said rotatable condenser member relative to the fixed condenser member.

20 2. In an electric condenser, stationary and movable condenser plates, a shaft supporting the movable plate, and manually operable coacting cam parts for shifting the movable plate axially of said shaft.

25 3. In an electric condenser, a stationary condenser plate, a non-rotatable condenser plate opposed to said stationary plate and provided with a cam part, and a rotatably mounted manually operable cam part coacting with the cam part on said condenser plate to adjustably space said electric condenser plate from the fixed plate.

30 4. In an electric condenser, a fixed condenser plate, a non-rotatable condenser plate opposed to said fixed plate and provided with a cam part, a spring normally urging 35 said non-rotatable plate towards the fixed plate, a dielectric interposed between the opposed surfaces of said plates, and a manually rotatable cam part coacting with the cam part on said condenser plate to shift the

same against the action of said spring and 40 vary the space between one of said plates and the dielectric.

5. In an electric condenser, primary and secondary capacity adjusting means, said primary means including a non-rotatable 45 axially shiftable condenser plate, and said secondary means including a rotatable condenser plate, and manually operable means for independently adjusting said movable condenser plates.

50 6. In an electric condenser, primary and secondary capacity adjusting means, said primary means including a non-rotatable axially shiftable condenser plate, and said secondary means including a rotatable condenser plate, coacting cam parts for shifting said primary condenser plate, and independently operable means for imparting a rotary movement to the secondary condenser plate.

55 7. In an electric condenser, a casing having opposite side walls constituting fixed condenser members, two movable condenser members mounted within the casing in opposed relation to the respective fixed condenser members, means for imparting a 60 rotary movement to one of the movable condenser members to position the same with relation to the opposed fixed condenser member, and additional means for imparting an independent lateral bodily movement to the 70 other movable condenser member towards or away from the other fixed condenser member.

65 In testimony that I claim the foregoing as my invention, I have signed my name 75 hereunder.

RUDOLPH KNOPP.
